UNITED STATES PATENT OFFICE.

ALBERT WOLF, OF TRAVERSE CITY, MICHIGAN.

SHAVING SET.

1,257,775.

Specification of Letters Patent. Patented Feb. 26, 1918.

Application filed July 6, 1917. Serial No. 178,967.

To all whom it may concern:

Be it known that I, ALBERT WOLF, a citizen of the United States, residing at Traverse City, in the county of Grand 5 Traverse and State of Michigan, have invented certain new and useful Improvements in Shaving Sets, of which the following is a specification.

This invention relates to toilet articles 10 and has special reference to shaving sets, the object of the invention being to provide in compact form means for permitting the easy carrying of a shaving brush, shaving soap and toilet powder. The invention 15 seeks to provide a construction which will permit the articles to be detachably connected and inclosed when not in use and readily separated when desired for use.

In the accompanying drawings:

20 Fig. 1 is a side elevation of a toilet article embodying my invention;

Fig. 2 is a longitudinal section of the same;

25 Fig. 3 is a detail view of the brush removed;

Fig. 4 is a detail view of the shaving soap and its holder removed;

Fig. 5 is a similar view of the toilet powder container;

30 Fig. 6 is an enlarged diametrical section through the upper end of the powder container.

In carrying out my invention, I employ a shaving brush 1 having a cylindrical handle 2 which is hollow and is internally threaded at one end, as shown at 3, and at its opposite end, adjacent the bristles, is externally threaded, as shown at 4. The soap holder consists of a ring 5 having a transverse partition 6 against which the end 35 of the soap stick 7 may rest and at one side of the said partition the ring is internally threaded to engage the external threads upon a sleeve 8 which is adapted to fit over the shaving brush 1 and is internally threaded at one end to engage the external threads on the shaving brush handle. This sleeve 8 is provided with perforations 9 near its ends so as to permit ventilation 40 of the brush and prevent moisture being retained therein to an injurious degree. The ring 5 is constructed to fit closely around the soap stick 7, as shown at 10, and upon the said portion 10 of the ring are external threads 11 which may be engaged by internal threads at the open end of a cap 12

which is adapted to fit over the stick and protect the same from deposits of dust or other germ-carrying elements. The powder container or receptacle 13 is externally threaded, as shown at 14, near its basal end, so as to engage the internal threads 3 of the brush handle, and immediately adjacent the said threads 14 the container may be annularly expanded to provide a stop 60 rim 15 adapted to engage against the end of the handle and thereby prevent the container being driven so far into the handle that it may not be easily withdrawn. The container will be constructed with a reduced 65 neck 16 having a perforated diaphragm 17 across its end to permit the powder to be sifted out when needed and upon the said neck is fitted a collar 18 adapted to hold an antiseptic pencil 19.

75 When the article is not in use the powder container will be housed within the handle 2 of the brush and the brush will be inclosed and protected by a sleeve which constitutes a connection between the brush handle and 80 the soap holder and the soap will be protected and inclosed by a cap fitting thereon and closely engaging the holder. It will thus be seen that the several articles are effectually protected against the collection 85 of dirt or other foreign matter and yet are readily accessible when needed for use. The powder container may be left in the brush handle until after the operation of shaving has been completed and will then form a 90 firm support for the brush so that it may be placed upon the lavatory in an upright position and will not be left to roll around the same and possibly fall upon the floor. A few turns of the cap and of the soap holder 95 will serve to separate them from each other and from the brush so that they may be instantly arranged for use and the protecting sleeve around the brush may be as quickly and easily withdrawn therefrom. Waste of 100 the toilet powder will be prevented by the presence of the collar 18 over the discharge end of the container but the collar may be easily and quickly removed when it is desired to use the powder. The device is exceedingly simple in the construction and arrangement of its parts and will retain them in compact form so that it will be found very convenient for travelers.

110 Having thus described the invention, what is claimed as new is:

1. A toilet article comprising a brush hav-

- ing a hollow handle externally threaded at the base of the brush and internally threaded at its open end, a container engaging the internal threads at the inner end of the handle and having an annular rim adapted to abut said end, an open-ended protecting sleeve fitting around the brush and engaging the external threads on the handle and provided with external threads at its end
- 6 remote from the handle of the brush, a ring having an internally threaded end fitting around the externally threaded end of the sleeve and constructed with an internal partition to extend across said end of the sleeve,
- 10 the end of the ring beyond the partition being externally threaded, and a cap having one closed end and one open end, the open end being internally threaded to engage the externally threaded end of the ring.
- 15 2. In a device of the character described, a brush having a hollow handle, a receptacle normally closed with respect to the brush handle and removably fitted in the outer end thereof, a protecting sleeve open at its ends and detachably connected at one end to the inner end of the brush handle; and a cap removably fitted upon the outer end of the said sleeve for closing the sleeve to house the brush therein.
- 20 3. In a device of the character described, a brush having a hollow handle, a receptacle normally closed with respect to the handle and removably fitted in the outer end thereof, the outer end of the receptacle pro-
- viding a base for the brush handle whereby the brush may be rested in vertical position supported by the said base to be normally held in such position by the weight of the receptacle, and means detachably connected at one end to the brush handle for housing the brush, the said means being open at both ends and provided at its outer end with a removable closure whereby the said means may be displaced from the brush handle and cleansed through its open ends.
- 40 4. In a device of the character described, a brush having a handle, a sleeve open at its ends and connected at one end to the handle to fit around the brush, and a cap connected to and closing the opposite end of the sleeve, the sleeve being detachable from the cap and handle to permit cleansing of the sleeve through the open ends thereof.
- 45 5. A toilet article comprising a brush having a hollow handle, a container removably fitted in the open end of said handle, a protecting sleeve removably fitted upon the brush at the base of the brush and extending around and over the brush, a ring threaded onto the outer end of said protecting sleeve and having an internal partition extending across and abutting the same, the ring beyond said partition being adapted to hold a soap stick, and a cap threaded onto the outer portion of the ring and extending over and around the stick carried thereby.

In testimony whereof I affix my signature.
ALBERT WOLF. [L. s.]
